[57] ABSTRACT

A magnetic field is used to deflect and separate the charged particles of an ion beam to impinge on successive areas of a long dielectric crystal according to the charge-mass ratio of the particles. After exposure to the deflected ions, a heated wire is moved over the crystal to produce thermoluminescence in the crystal that is detected with a bank of phototubes. The resulting signals from the phototubes are correlated with the areas of the crystal and counted to indicate the spectrum of the particles.

THERMOLUMINESCENT DETECTOR FOR MASS SPECTROMETER

ORIGIN OF THE INVENTION

The invention disclosed herein was made under, or in, the course of Contract No. W-7405-ENG-48 with the United States Atomic Energy Commission.

BACKGROUND OF THE INVENTION

This invention pertains to an ion detector for a mass spectrometer, and more particularly, it pertains to a thermoluminescent crystal as an integrating ion detector for a mass spectrometer.

The usual ion detector in a high-resolution double-focussing mass spectrometer is a photoplate which is located in a vacuum area of the spectrometer. The photoplate must be removed from the spectrometer to be chemically developed and analyzed. Such removal requires exposing vacuum areas of the spectrometer atmosphere. Thereafter these areas must be pumped down to restore the vacuum. Prior to each pump-down a new photoplate is replaced in the spectrometer. The new photoplate tends to outgas and thereby prolong the pump-down time. The typical photoplate-equipped spectrometer is thus limited to analyzing only a few samples per day. Another disadvantage of the photoplate detector is its relatively limited dynamic range — about 100. This means that the highest ion exposure still in the linear response range of the photoplate is only 100 times greater than the lowest detectable exposure. Ideally a detector should have a dynamic range much greater than this so as to provide a linear response over a very wide exposure range, thus eliminating the need for running either multiple calibration curves or replicate exposures per sample.

SUMMARY OF THE INVENTION

In brief, the present invention pertains to an ion detector for a mass spectrometer, including means for establishing a magnetic field of specific strength; means for injecting an ion beam of various charged particles to pass through the field at right angles to the lines of the field, thereby causing the charged particles to follow divergent curved paths according to the charge-mass ratio of the particles, each of the paths terminating at a focal point in a focal plane; a dielectric crystal positioned in the focal plane of the particle paths so that the charged particles impinge on the crystal at respective focal points to create trapped electron-hole pairs in the crystal, the number of pairs at each point being proportional to the total exposure time of the crystal to charged particles impinging at that point and thus the number of particles; means for heating the crystal to cause recombination of the electron-hole pairs to cause thermoluminescent emission from the exposed areas; means for transducing the thermoluminescence of each area to electrical pulses; and means for counting the electrical pulses corresponding to each area to determine the total exposure of each area and hence the mass spectrum of the ion beam.

It is an object of the invention to obtain a mass spectrum of an ion beam injected into an evacuated space without disturbance of the vacuum.

Another object is to provide an ion detector with a dynamic range greater than 10^6 .

Another object is to determine successive mass spectra rapidly and efficiently.

Another object is to provide an ion detector with increased sensitivity.

Other objects and advantageous features of the invention will be apparent in a description of a specific embodiment thereof, given by way of example only, to enable one skilled in the art to readily practice the invention which is described hereinafter with reference to the accompanying drawings.

BRIEF DESCRIPTION OF THE DRAWINGS

FIG. 1 is a cross-sectional diagram of a spectrometer in which an ion detector, according to the invention, is mounted.

FIG. 2 is a family of typical log-log curves illustrating the linearity and dynamic range of the ion detector of FIG. 1.

FIG. 3 is a representative general sensitivity curve 20 that may be derived from the curves of FIG. 2 and is useful for analyzing unknown beams.

DESCRIPTION OF AN EMBODIMENT

Referring to the drawing there is shown in FIG. 1 a mass spectrometer 11 in which an ion beam 13 is injected between energy limiting electric sectors 15 into a magnetic field 17 produced by a magnet 16. The ion beam is injected at right angles to the magnetic field which causes the beam to diverge and follow curved paths 18 according to the charge-mass ratio of the various ions of which the beam is composed. A dielectric crystal 19, conveniently a single elongated crystal, is positioned in the focal plane of the divergent beams and is comprised of successive continuous areas on which the divergent beams impinge, each area being representative of ions of a particular energy and charge-mass ratio for a magnetic field of specific strength. Trapped electron-hole pairs are created in the crystal at each focal point in a number that is proportional to the total exposure time of the crystal to the portion of the beam impinging at each point.

When it is desired to determine the number of particles that has impinged on the various areas of the crystal, an electric heating element such as a wire 21, which is mounted adjacent and in brushing contact with the crystal 19, is electrically heated and then moved over the surface of the crystal by means of a stepping motor 23 and flexible belt 24, causing successive areas of the crystal to heat and luminesce as the wire is stepped over the crystal. A bank of photo-tubes 25 are mounted adjacent the crystal 19 with all of their outputs connected together to a computer 27. The steps of the stepping motor may be correlated with the mass of the particles impinging on each area of the crystal, each step corresponding to a particular mass. The motor is also connected to the computer which is programmed to accumulate the number of counts from the photo-tubes for each step of the motor and to translate the counts for a particular mass to coulombs. After the wire 21 has been moved over the entire crystal, the computer totals together the coulomb exposure of all areas and then prints out as a fraction of the total exposure the amount of exposure of each area corresponding to each step of the motor. Such a printout, therefore, is a direct indication of the mass spectrum of the beam 13. The wire 21 is returned to its original position and the spectrometer is ready for the next analysis.

In operation, the spectrometer 11 may be calibrated with known beams to ascertain the areas on which known ions will impinge and to obtain a family of curves 26 as shown in FIG. 2, where each area of the crystal corresponds to one of the curves, the curves of greater slope corresponding to particles of smaller mass. A general sensitivity curve 28 such as shown in FIG. 3 may be derived from any two or more curves 26 by picking a number of counts such as 10^3 and plotting the coulombs/number of counts as a function of the mass of the particle. The curve 28 may be programmed into the computer so that at each step of the motor an adjusted value of coulombs per 1,000 counts is used to determine the correct exposure in coulombs at each step. Since the curves 26 are linear, the curve 28 is also linear and may be used for all masses. Thereafter, all ion beams may be analyzed without further calibration of the spectrometer as long as the energy of the beam 13 and the strength of the field 17 are maintained at the levels maintained during calibration or at adjusted levels that provide identical ion deflection.

The sensitivity of detection of the crystal 19 can be increased by maintaining the crystal at a cryogenic temperature to prevent emptying of shallow lattice traps which otherwise empty at room temperature. Such cooling may be accomplished by circulation of liquid nitrogen from a cryogen pump and reservoir 29 through cooling coils 31 around the crystal 19.

Various types of dielectric crystals may be used for the crystal 19, for example fused quartz. The structural strength of fused quartz in addition to its commercial availability in large sizes and the energy depth of its lattice traps make it a desirable crystal. However, many other crystals may be used as well.

In a practical embodiment of the invention, a beam of $^{27}\text{Al}^+$ ions were directed to impinge on a dielectric crystal of dysprosium-doped calcium fluoride. The crystal was heated and a log-log plot of total exposure to the ion beam versus the photomultiplier counts is shown in FIG. 2. The plot indicates a linear dynamic range of 10^6 (10^{-8} coulombs/ 10^{-14} coulombs).

While an embodiment of the invention has been shown and described, further embodiments or combinations of those described herein will be apparent to those skilled in the art without departing from the spirit of the invention.

What I claim is:

1. A mass spectrometer including:

means for establishing a magnetic field within said spectrometer;
means for injecting an ion beam of charged particles to pass through said field at right angles to the field lines of said field, said field causing the charged

particles to follow divergent curved paths according to the charge-mass ratio of the particles, each of said paths terminating at a focal point in a focal plane;

a dielectric crystal positioned in the focal plane of the particle paths, said charged particles impinging on said crystal at respective focal points to create trapped electron-hole pairs in the crystal, the number of pairs at each point being proportional to the total exposure of the crystal to charged particles impinging at that point;

means for heating said crystal to cause recombination of the electron-hole pairs, said recombination causing thermoluminescent emission from the exposed areas;

means for transducing the thermoluminescence of each area to electrical pulses; and
computer means for counting the electrical pulses corresponding to each area to thereby determine the mass spectrum of the ion beam.

2. The spectrometer of claim 1 wherein said crystal is a single elongated crystal.

3. The spectrometer of claim 1 wherein said crystal is fused quartz.

4. The spectrometer of claim 1 wherein said crystal is dysprosium-doped calcium fluoride.

5. The spectrometer of claim 1 wherein said injecting means includes an electric sector for passing ions of a selected energy into said magnetic field.

6. The spectrometer of claim 1 wherein said heating means includes means for sequentially heating successive areas of said crystal.

7. The spectrometer of claim 1 wherein said heating means includes a wire, means for heating the wire, and means for moving the wire over said crystal to heat said crystal.

8. The spectrometer of claim 7 wherein said moving means is a stepping motor, and said computer means is operable for counting the steps of the motor, for counting the number of electrical pulses corresponding to each area, for correlating the number of pulses for each area with each step of the motor, for counting the total number of electrical signals, and for indicating the counts corresponding to each area as a fraction of the total counts from the crystal.

9. The spectrometer of claim 7 wherein said cooling means includes means for cooling said crystal to a cryogenic temperature with liquid nitrogen.

10. The spectrometer of claim 1 further including means for cooling said crystal to maintain shallow lattice traps in said crystal filled with background to increase the sensitivity of the crystal.
